US0D1009410S

(12) **United States Design Patent** (10) **Patent No.:** **US D1,009,410 S**
(45) **Date of Patent:** **** Jan. 2, 2024**

(54) **PANTS**

(71) Applicant: **Wei Xun**, Xi'an (CN)

(72) Inventor: **Wei Xun**, Xi'an (CN)

(**) Term: **15 Years**

(21) Appl. No.: **29/829,571**

(22) Filed: **Mar. 7, 2022**

(51) LOC (14) Cl. **02-02**

(52) U.S. Cl. **D2/731**
USPC ....

(58) **Field of Classification Search**

USPC **D2/728, 731, 742, 853**

CPC **A41D 1/06; A41D 1/08**

See application file for complete search history.
